UNITED STATES PATENT OFFICE

GEORGE E. WINTZ, OF NEW YORK, N. Y.

TALKING BILLBOARD

Application filed September 11, 1929. Serial No. 391,952.

This invention relates to improvements generally in advertising apparatus but specifically in billboards and other forms of display advertising, and it consists of the 5 constructions, combinations and arrangements herein described and claimed.

An object of the invention is to provide a billboard with features that will compel attention for more than a brief period.

10 Another object of the invention is to provide a billboard with a pictorial illustration and some broadcasting apparatus for producing sounds characteristic of the illustration.

15 A further object of the invention is to provide a billboard with the picture of a human figure, at least in part, and an apparatus which will cause the features to simulate speech both as to sound and action.

20 A still further object of the invention is to provide the combination of a billboard and a phonograph, with means on the billboard forming part of a pictorial illustration and being moved either by the motor of the 25 phonograph or by a disk complementary to the phonograph record but having a deeper groove cut therein, with means to be actuated by the rise and fall in the contour of the groove so that the motion of said means on 30 the billboard and the sounds issued by the phonograph will occur in synchronism and be characteristic of said illustration.

Other objects and advantages will appear 35 in the following specification, reference being had to the drawings, in which:—

Figure 1 is a perspective view of a part of the improved billboard particularly exemplifying the invention by the illustration of a 40 part of a human figure.

Figure 2 is a sectional view of the cabinet immediately behind the billboard, the apparatus for simulating speech by sound and action being shown in elevation.

45 Figure 3 is a vertical section taken on the line 3—3 of Figure 2.

Figure 4 is a detail view illustrating how motion is imparted to one of the eyes.

50 Figure 5 is a detail vertical section taken on the line 5—5 of Figure 2.

Figure 6 is a detail perspective view of the so-called lip plate.

Figure 7 is a detail front elevation illustrating the action of the lip plate in simulating speech.

55 Figure 8 is a plan view, partially in section, illustrating a modification in which a disk complementary to the phonograph record is employed in the operation of the lip plate and eye disks.

60 Figure 9 is a section taken on the line 9—9 of Figure 8.

Figure 10 is a detail cross-section taken substantially on the line 10—10 of Figure 8.

65 Figure 11 is a perspective view of the pinion and a portion of the rack bar, particularly illustrating the retainer by which the two are loosely connected.

70 Figure 12 is a cross-section of the telescopic shaft taken on the line 12—12 of Figure 8.

Figure 13 is a cross-section taken on the line 13—13 of Figure 8.

75 As has been indicated already in the foregoing brief statements, the purpose of the invention is to produce a more compelling advertising medium. To this end, use is made of a billboard of any size and when periodical displays are intended on a small scale, the billboard can be stood up in a window or lobby of a theater, at a stand, or put in a box in front of business places. The idea is to enable utilization of the invention on any size of billboard so that the advantages of the invention may be had both indoors and outdoors. But rather than to rely on such pictures or printed matter which may be applied to the billboard for bringing the advertised matter to the attention of the public, an apparatus is associated with the billboard for imparting some degree of animation to the picture by causing motions and sounds including the voice characteristic of the picture.

80 85 90 95 While these premises intentionally permit a wide range for the application of the principles of the invention, the illustration of the latter is confined to that of a part of a human figure which is made to simulate speech. A phonograph is used for the purpose, and in addition to producing the characteristic 100

sounds of speech its clockwork or other motor is used to actuate a lip plate which will simulate the action of speaking.

Attention is directed to the drawings. A billboard 1 is supplied with a picture 2 of the head and bust of a woman. The billboard has eye openings 3 and a mouth opening 4. The former possess the more or less characteristic shape of elliptical slits, while the opening 4 is of rectangular formation. Another opening 5 in the billboard is the point at which sounds from the reproducer 6 of a phonograph 7 are issued. This opening is screened at 8, partly to prevent the entrance 10 of foreign matter, but more particularly to enable painting thereover so that the presence 15 of the opening will be disguised.

A tube 9 connects the opening with the tone arm 10 of the phonograph. The stylus of the reproducer 6 traverses the record 11 in the characteristic manner. In practice, the phonograph will be equipped with a repeating device of which there are several types on the market, the purpose of which is to return 20 the tone arm 10 to the starting position at the periphery of the record when the inner end of the sound groove has been reached by the stylus.

The motor 14, which in practice may either 30 be of the spring or electrical type, but preferably is of the latter, drives both the turntable 15 and a countershaft 16 which, in turn, has gear connections 17 with a driven shaft 18 which is mounted in bearings 19 on one side 35 of the phonograph casing 20. A cam 21 on the shaft 18 bears against a roller 22 which is journaled on the upstanding arm 23 of a slide 24.

A slot 25 in the slide 24 receives a pair of 40 studs 26 which are driven into the back of the billboard 1 (Figure 5) and carry sleeves 27 by which the slide 24 is spaced an appropriate distance from the back of the board. The studs 26 guide the slide. The motion of the slide is rectilinear and this motion is imparted by the action of the cam 21 against the roller 22. A spring 28, attached at its respective ends to the slide 24 and to a wall of a cabinet 29 by which the apparatus is enclosed, exerts a pull on the slide in one direction, thus 50 maintaining the roller 22 in proper contact with the periphery of the cam.

Links 30 loosely connected with the slide 24 55 by means of pins 21 and slots 32 are secured to so-called eye disks 33 each of which has an eye-ball 34 painted or otherwise indicated on the front surface at a point near the lower periphery. Both a screw 35 and a pin 36 serve to secure the upper end of the link 30 to the respective disk (Figure 3), the screw 35 serving as a pivot upon which the disk rocks behind the eye opening 3. To this end, the screw 35 is driven into the bulletin board, and 60 in order that the eye-ball 34 may appear as

near to the front surface of the billboard 1 as possible, the latter is recessed at 37 to receive and contain the eye disk 33.

As the disks 33 rock upon the pivots 35, the eyeballs 34 traverse the openings 3 from the full line position in Figure 4 to the dotted line position 38, thus imparting a degree of animation to the figure. The mouth is also animated in part, and to this end, the lower lip 39 (Figures 1, 6 and 7) is painted upon 75 the front flange 40 of a so-called lip plate generally designated 41. The inner portion 42 of this plate which is parallel to the flange 40 has slots 43 (Figure 2) to receive screws 44 by which the lip plate is not only guided but by which the inner portion 42 is held in bearing engagement against the back of the billboard 1.

A roller 45, carried by the inner portion 42, 80 engages an edge of the slide 24, being pressed into such engagement by a spring 46 which is seated upon a rest 47 and bears against a heel 48 in which the portion 42 terminates. The foregoing edge of the slide 24 is provided with a plurality of lobes 49 which are spaced 90 apart and are intended to intermittently depress the lip plate 41 against the tension of the spring 46 as the slide 24 moves back and forth, thus imparting a quivering motion to the lip 39 to simulate the act of talking.

Attention is now directed to the modified form of the invention in Figures 8 to 13. The principle is identical with that of the form of the invention already described but the specific mode of operating the lip plate 41 and 95 the eye disks 33 is different. A disk 50, complementary to the phonograph record 11, is carried by a turntable 51 which is driven in synchronism with the turntable 15 by gearing generally designated 52.

The groove 53 (Figures 8 and 10) will be cut very much deeper than the sound groove in the record 11, and in this instance, the groove 53 becomes the medium by which the lip plate and eye disks are actuated through 100 an intermediary mechanism. The purpose is to move the lip plate and eye disks, especially the lip plate, in harmony with the speech or song so that the impression of animation will become more realistic. For example, if the record 11 contains a sales talk or a song, the lips will move in accordance 115 with the voice.

This is accomplished by providing a secondary stylus 54 to follow the contour of the groove 53. The stylus is carried by an arm 55 that has connection with a rack bar 56. The rack 57 of this bar engages a pinion 58 fixed on one component of a telescoping shaft 59. The other component of the shaft carries a gear 60 which is larger than the pinion 58. The gear actuates the lip plate 41, for which purpose the inner portion 42 is regularly perforated at 61 to provide teeth with which the gear 60 meshes.

A stud 62 carries a screw 63 which provides a pivotal mounting for the arm 55. A very light spring 64, affixed at one end to the stud and hooked over the arm 55 at the other 5 end, supplies sufficient pressure to keep the stylus 55 in engagement with the groove 53. A swivel connection 65 of the stud with a fixed bracket 66 accommodates the necessary arcuate turning of the arm 55 as the stylus 10 follows the groove.

There must be some degree of looseness between the rack 57 and the pinion 58 because the arcuate motion of the outer end of the arm 55 must be taken into account. The bar 15 56 is pivoted to the arm 55 at 67. A retainer 68 makes a loose connection between the bar 56 and the shaft 59. This retainer is nothing more than a strap of metal provided with an elongated perforation 69 through which one 20 of the components of the shaft 59 extends and having its ends looped around the rack bar.

The purpose of the retainer 68 is to cause the slideable component of the telescoping shaft as well as the pinion 58 to move with 25 the rack bar as the latter traces an arcuate path while the stylus 54 is traversing the groove 53. It is the slight change in position of the rack 57 in respect to the pinion 58 that must be compensated for by the loose engagement 30 of the rack with the pinion during the foregoing period. A pin 70 in the slideable component provides a bearing for one side of the retainer. The pinion 58 provides a bearing for the other side, while the retainer 35 pushes against one or the other to slide the shaft.

A bracket 71 supports the outer end of the slideable shaft component. This end occupies a slot 72 in the bracket. The slot is necessary to permit a slight shifting of the shaft as the outer end of the arm 55 makes its arcuate movement. The components of the telescoping shaft 59 are slidably connected at a cross-sectional non-circular place (Figure 45 12). This permits relative sliding but compels uniform turning.

The other component of the telescoping shaft has support on a bracket 73. It has a pin 74 on each side of the bracket for the 50 purpose of preventing longitudinal displacement. The bearing of the shaft in the bracket 73 is loose so that any horizontal swinging at the right end is readily compensated for. A crank pin 75 on the gear 60 has connections 55 76 and 77 with one of the eye disks 33, the links 30 of which are connected by a rod 78 so that there may be uniform turning of the disks as in the first instance.

The operation is readily understood. The 60 motor 14 is the common source of motive power for the phonograph 7, the supplemental turntable 51 (in the instance of the modification), and for the designated features of the picture 2. Considering first the 65 first form of the invention, the phonograph

record 11 will have recorded thereon such sounds as may be deemed most appropriate for the particular advertisement on the billboard 1. These sounds may comprise either speech or song.

When speech is employed, it will be composed to address the passerby in a purely informal manner, for example: "Hello, Fred, have you had your 'Lucky' today?" etc. Any passerby will be attracted by the voice, and 70 since "Fred" is a popular name, there is the possibility that quite a number of persons will be particularly attracted by hearing themselves so familiarly addressed.

As the sounds of speech continue to issue 80 at the opening 5, they will be accompanied by a rocking motion of the eye-balls 34, thus further directing attention to the particular advertisement. At the same time, the lower lip 29 will quiver, thus making it appear as though the woman were actually speaking. In practice, the front flange 40 will not be nearly so prominent as in the drawings, and by countersinking the flange, its presence 85 could be made almost imperceptible. All 90 that the observer would then see would be the moving lower lip.

Consider next the modification in Figures 8 to 13. The sole idea of the supplemental disk 50 is to make it appear as though the 95 lower lip 39 were actually articulating the speech or song. With the arrangement in the figures preceding Figure 8 the lip will merely quiver with a uniform motion, but with the arrangement in Figures 8 to 13, the motion of the lip will be variable but in synchronization with the actual speech or song. The eyes are made to move as well, and since 100 these are connected with the gear 60, the motion will be variable rather than uniform 105 as in Figure 2.

To these ends, the groove 53 is cut with some degree of similarity to the sound groove in the record 11. Of course, the multitudinous microscopic undulations of the sound groove will be omitted but the main characteristic of the groove 53 will be the same as that of the sound groove. The groove 53 will be much coarser. It will be much deeper in places, as suggested in Figure 10, so that it 110 will produce a sufficiently distinct action of the arm 55 to be transmitted through the intermediary mechanism 56, 59 and 60 to the lip plate.

It has been stated in respect to the first 115 construction that some known type of repeating device will be used to return the tone arm 10 to the original position after the record has been played. A similar arrangement 120 will be employed in connection with the modification. A pair of the repeating devices will be used, one for the return of the tone arm 10, the other for the return of the arm 55. These devices are not illustrated because 125 there are several known types on the market 130

and such one as will best serve the purpose will be selected for actual use.

The source of speech is not necessarily confined to a phonograph record. Any broadcasting apparatus may be employed. The combination then comprises a billboard with a pictorial illustration and suitable advertising matter and a broadcasting apparatus for producing sounds appropriate to said 10 illustration.

While the construction and arrangement of the improved talking billboard is that of a generally preferred form, obviously modifications and changes may be made without 15 departing from the spirit of the invention and the scope of the claims.

I claim:—

1. Advertising apparatus comprising means having a pictorial aspect, a movable 20 member being part of said means, a revolute disc having a spiral undulated groove, movable means having a stylus to follow the groove, linkage attached to said means to which its movements resulting from the action 25 of the stylus are imparted, a telescopic shaft which is oscillated by said linkage by virtue of the undulations of the groove and telescoped by virtue of the radial displacement of the stylus, and means for imparting 30 the oscillation of the shaft to said movable member.

2. Advertising apparatus comprising means having a pictorial aspect, a movable member being a part thereof, a telescopic 35 shaft having means for imparting movements to said member, a revolute disc having a spiral undulated groove, an arm having a stylus to follow the groove, means by which the arm is supported for rocking movements in two directions to compensate for the undulations of the groove and the radial displacement of the stylus, a meshing rack and pinion respectively carried by the arm and shaft, and means to keep the rack and pinion 40

45 in mesh to maintain the oscillations of the shaft while said rack and pinion shift in accordance with said displacement of the stylus.

3. Advertising apparatus comprising means having a pictorial aspect, a movable 50 member being part of said means, a revolute disc having a spiral undulated groove, movable means having a stylus to follow the groove, linkage attached to said means to which its movements resulting from the action 55 of the stylus are imparted, a telescopic shaft which is oscillated by said linkage by virtue of the undulations of the groove and telescoped by virtue of the radial displacement of the stylus, means for imparting the 60 oscillation of the shaft to said movable member, apparatus for producing sounds to accompany the movements of the movable member, and means by which the revolutions of the revolute disc are derived from said 65 apparatus.

4. An apparatus comprising movable eye and lip members, sound reproducing apparatus, and means to produce irregularities of movement of said members in approximate agreement with the irregularities of the sound reproduced by said apparatus. 70

5. An apparatus comprising movable eye and lip members, sound reproducing apparatus, and means operating in conjunction with said apparatus to impart continuously varied movements to said members in approximate conformity to the vibrational values of the sound of said apparatus. 75

6. An apparatus comprising movable eye and lip members, sound reproducing apparatus, an element simulating a phonograph record, means to actuate said apparatus and record at the same time, and means to translate the irregularities of the record groove into irregular movements of said eye and lip members in accompaniment to the sound reproduction. 80

7. An apparatus comprising movable eye and lip members, an element simulating a phonograph record, means to rotate said element, and means for communicating the undulations of the groove in said element to said eye and lip members. 85

8. An apparatus comprising a movable member forming part of a pictorial representation, an element simulating a phonograph record, means to rotate said element, and means for converting the undulations of the groove in said element into movements of said member. 90

9. An apparatus comprising a movable member forming part of a pictorial representation, movable grooved means for animating said member, a shaft having connection with said movable member, rack and pinion elements, one of the elements being carried by the shaft, an arm carrying the other element, and means on the arm to follow the groove. 100

10. A pair of revolute elements each having a spiral, undulating groove of which one is a sound groove, a reproducer coacting with the sound groove, an element having a stylus coacting with the other groove, a movable member comprising part of an advertising apparatus, connecting and actuating means between the element and said member, and means for driving said revolute elements at the same time thus to produce sounds in accompaniment to the movements of said member. 110

GEORGE E. WINTZ.
